CLAIM

The ornamental design for a balloon holder, as shown and described.

DESCRIPTION

FIG. 1 is a front, right and top perspective view of a balloon holder, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is an enlarged top plan view thereof.

FIG. 8 is an enlarged bottom plan view thereof.

FIG. 9 is an enlarged view of detail 9 in FIG. 1.

FIG. 10 is an enlarged view of detail 10 in FIG. 2; and, FIG. 11 is another front, right and top perspective view of the balloon holder in another state.

The evenly spaced broken lines are for purposes of illustrating portions of the balloon holder that form no part of the claimed design; The dash-dot broken lines are for annotative purposes only and form no part thereof.
